UNITED STATES PATENT OFFICE.

BERNARD J. CUNNINGHAM, OF CORONA, NEW YORK.

BOTTLE.

1,158,987.

Specification of Letters Patent.

Patented Nov. 2, 1915.

Application filed April 29, 1915. Serial No. 24,777.

To all whom it may concern:

Be it known that I, BERNARD J. CUNNINGHAM, a citizen of the United States, residing at Corona, in the county of Queens and State of New York, have invented certain new and useful Improvements in Bottles, of which the following is a specification.

This invention relates to bottles, and has particular utility when applied to nursing bottles, which it is especially desirable to 10 keep perfectly sweet and clean.

The object of the invention is to provide a bottle which can be thoroughly washed and cleaned, and to this end, I have devised 15 a bottle having a removable bottom and provided with means for firmly holding the same in position when the bottle is in use.

In order that the invention may be readily understood, reference is had to the accompanying drawing, forming a part of this 20 specification, and in which,

Figure 1 is a vertical, central section through my improved bottle; Fig. 2 is a similar section on a plane at right angles 25 to that of Fig. 1, parts being in elevation; and, Fig. 3 is a plan view on an enlarged scale of a special construction of cap, hereinafter described.

Referring to the drawings in detail, my 30 improved bottle comprises a body 1, having the usual neck 2. The bottom 3 of the bottle is removable and may conveniently be formed of hard rubber, or the like. Rigidly secured to the center of the bottom and preferably integral therewith, is a connecting member 4, which extends upwardly through the neck of the bottle and projects beyond the upper edge thereof, as indicated at 6. This connecting member may be of any suitable 35 form, but is shown as consisting of a tube, cut away on its sides, as indicated at 5, so that the liquid may readily flow into the same from the bottle and out through that portion of the tube which passes through the neck. In order to hold the bottom in 40 position, I provide a cap 7, fitting over and having a screw-threaded engagement with the projecting end 6 of the connecting member, the lower edge of such cap bearing 45 against and being supported by the upper end of the neck 2. The edge of the bottom 3 is preferably rabbeted, as indicated at 8. A packing ring 9 of soft rubber, or the like,

is interposed between the bottom and the edge of the bottle body to secure a tight 55 joint.

In the case of a nursing bottle, a suitable nipple (not shown) may be fitted directly to the cap 7, or if the bottle is to be used for other purposes, a suitable closure may be 60 provided. As illustrated in Fig. 3, a convenient construction consists in a disk 10, pivoted to the cap 7 at 11 and capable of swinging laterally so as to cover and uncover the opening in a well known manner. 65

It will be seen that by virtue of the hollow connecting member 4, the free flow of liquid through the bottle neck is permitted at all times, and by unscrewing the cap 7, the bottom and connecting member may be 70 removed so that the parts may be subjected to individual cleaning and sterilization.

What I claim is:

1. The combination with a bottle body, of a removable bottom therefor, and means 75 extending through the inside of the bottle for holding said bottom in position, such means permitting the free passage of liquid through the neck of the bottle in the usual manner. 80

2. The combination with a bottle body, of a removable bottom therefor, a connecting member extending upwardly from the bottom through the neck of the bottle, and means outside of the neck for securing said 85 member in position.

3. The combination with a bottle body, of a removable bottom therefor, a connecting member extending upwardly from the bottom through the neck of the bottle, and a 90 screw cap engaging said member, and resting against the end of the neck.

4. A bottle comprising a body having the usual neck, a removable bottom, a hollow connecting member, open at the side, secured 95 to said bottom and extending upwardly through said neck, and a cap screw-threaded onto the projecting end of said member and bearing against the neck.

In testimony whereof I have affixed my 100 signature in presence of two witnesses.

BERNARD J. CUNNINGHAM.

Witnesses:

EUGENE F. GILES,
ROBERT A. DOYLE.
